UNITED STATES PATENT OFFICE.

HENRY J. DAVIES, OF BROOKLYN, NEW YORK.

DESIGN FOR A CLOCK-FRONT.

SPECIFICATION forming part of Design No. 14,501, dated December 25, 1883.

Application filed November 3, 1883. Term of patent 7 years.

To all whom it may concern:

Be it known that I, HENRY J. DAVIES, of the city of Brooklyn, in the county of Kings and State of New York, have originated and produced a new Design for the Fronts of Clock-Cases, of which the following is a specification, reference being had to the accompanying drawing.

My design for a clock-front consists in the figure of a butterfly, the dial being on the body and wings of the figure.

a b b c c in the drawing indicate the outline of the figure of butterfly. The dial is indicated by the circle of numerals arranged on

the body and wings of the figure, the center 15 of the dial being at or near the center of the figure.

What I claim, and desire to secure by Letters Patent, is—

The design for a clock-front, consisting in the 20 figure of a butterfly, with the clock-dial on the body and wings of the figure, herein described and shown.

HENRY J. DAVIES.
